UNITED STATES PATENT OFFICE.

GEORGE HOLT FRASER, OF BROOKLYN, NEW YORK.

AIR SEPARATOR.

Application filed March 8, 1919, Serial No. 281,445. Renewed September 19, 1924.

To all whom it may concern:

Be it known that I, GEORGE HOLT FRASER, a citizen of the United States, residing in the borough of Brooklyn, county of Kings, city and State of New York, United States of America, have invented certain new and useful Improvements in Air Separators, of which the following is a specification.

This invention relates to air separators for separating fine from coarse material, and aims to provide certain improvements therein.

Heretofore air separators have comprised a casing enclosing a chamber, an upper receptacle therein having upper and lower openings communicating with the chamber, a lower receptacle having an open upper end below and spaced apart from said lower opening and serving as a tailings cone for receiving coarse material therefrom, and affording communication between the receptacles for air returning from the outer chamber to the lower opening, a revolving distributing disc for feeding material to be separated into the upper receptacle, and a revolving fan above the upper receptacle for causing air to flow upwardly therethrough and outwardly into the chamber to float out fine material to the chamber where it may precipitate and whence the air may return between the receptacles.

My present invention relates particularly to separators of this character and aims to prevent floating particles from returning between the receptacles, to facilitate adjusting the space through which return current may flow, to simplify such devices, and to provide various improvements therein.

To this end in carrying out the preferred embodiment of my present improvements I provide foraminous means surrounding the space between the receptacles for intercepting floating particles in the current approaching such space, and I preferably provide a valve or means for varying the space through which current may pass through said foraminous means, and I preferably provide a stationary lower receptacle inwardly of said foraminous means and said valve and which serves as an upper wall for the lower part of said outer chamber and a lower wall for said return passage, and I preferably provide said valve as a vertically adjustable ring or cylinder within said annular means and between the latter and surrounding said lower receptacle, and I pref-

erably provide a downwardly adjustable annular valve fitting around the upper receptacle and adjustable toward the lower receptacle to vary the space between them, 60 and I provide various other features of improvement, all of which will be more fully hereinafter set forth with reference to the accompanying drawings, in which—

Fig. 1 is a vertical axial section showing 65 the preferred adaptation of my present improvements as applied to an inside blower air separator cut on the planes of the lines 1-1 in Fig. 2, and

Fig. 2 is a fragmentary horizontal section 70 thereof cut on the lines 2-2 in Fig. 1, and

Fig. 3 is a fragmentary vertical section 75 showing a modification, and

Fig. 4 is a diagrammatic view showing 80 my improved system and the connections and valves between the complementary parts thereof for regulating and controlling the operation of separating material.

Referring to the drawings A is the casing 85 of an air separator, B is the driving mechanism, C is the feed hopper, D is the distributor, E is the blower, F is the feed chamber, G is the outer chamber, H is the dust chamber, I is the return passage, J is the tailings 90 chamber, K is the upper receptacle and L is the lower receptacle.

The casing A usually has a flat top a, a cylindrical body b and a conical bottom c.

The driving mechanism usually comprises 95 a bearing frame M, a tubular shaft N, which revolves therein and carries the disc D and surrounds the adjustable feed pipe O which delivers the material to be separated on to the disc D, which latter is vertically adjustable on the shaft N. The blower E generally comprises outwardly adjustable tangential plates d carried from and revolved by the shaft N.

The upper receptacle has a wide or cylindrical body P, a contracting upper opening or neck Q, and a lower opening R, and is usually formed with an upper conical wall e, and a flat top or shelf f below the fan affording above the shelf an annular space 100 or clearance for the latter, and an annular outlet or passage S for current from the upper opening Q to the outer chamber G, and affording below the shelf an annular recess g. The bottom of the upper receptacle is usually a tapering or conical wall h.

The lower receptacle is a cone usually

spaced below the upper receptacle and having an open upper end *s* affording communication from the outer chamber to the lower opening *R*, so that when the fan operates 5 air can circulate through the upper receptacle and its upper opening and the outlet *S* to the chamber *G* and descend around the upper receptacle, and dust may precipitate in the chamber *H* and the air return between 10 the receptacles to the lower opening.

According to one feature of improvement I provide means as the filter *T* for intercepting particles in the air floating from the outer chamber toward the return passage *I* 15 between the receptacles, preferably providing a plurality of annular rows of vertically extending spaced troughs *i* surrounding the space between the receptacles and affording an annular interstitial wall for 20 the inner side of the outer chamber, the troughs having concave or hollow outer faces *j* opposed to the inflowing current and affording vertically extending ways through which intercepted material may 25 descend through and out of the current zone to the dust chamber without being molested by adjacent air currents, and being spaced or disposed to afford between their edges vertically extending apertures affording 30 horizontally or inwardly extending current passages *k* through which current may flow intermediate of said ways. Preferably two rows of such troughs are provided and the troughs of the inner row are staggered in 35 relation to those of the outer row so that their hollow faces are opposite the spaces between the outer troughs. The hollows of these troughs serve to hold relatively motionless air in the path of the approaching 40 current, so that any floating particles entering this calm may precipitate therein, and the current passing from the outer chamber to the return will be correspondingly cleaner.

45 These troughs are preferably mounted on or around the cylindrical part of the upper receptacle by being mounted on sectional arc shaped angle irons *l* suspended removably from the latter in such way that the 50 horizontal leg of the angle covers and closes the tops of the troughs to prevent current descending vertically between them, the troughs being bolted to the vertical leg of the angle, so that each trough, each row or 55 any sections, can be removed.

The lower receptacle or tailings cone *J* is 60 preferably stationary and disposed at the maximum distance desired below the upper receptacle, and its upper end preferably projects an appreciable distance above the lower ends of the filter troughs *T*, so that it serves as an upper wall for the dust chamber *H* within these troughs to isolate the chamber from the return current as well as 65 to receive and conduct outwardly coarse ma-

terial descending from the upper receptacle. The lower receptacle is preferably formed of a fixed upper section *m* and a fixed lower section *n* separably connected together, the upper section being preferably mounted by 70 posts *o* on the upper part *p* of the conical bottom *c* of the outer casing and the lower section *n* being separably or stationarily mounted by brackets *q* on the lower section *r* of the bottom of the outer casing so that the lower removable bottom *r* of the outer casing and the lower section *n* of the tailings cone may be removed together, but are separable so that the lower section of the tailings cone may be assembled previously to 75 applying the outer bottom.

According to another feature of improvement I provide means for varying the space within the filter *T* through which current may flow to pass between the receptacles, 80 preferably providing a vertically adjustable valve *U* within the filter *T* and surrounding the upper open end of the lower receptacle.

By raising the valve *U* the location of the outlet from the chamber *G* for return current may be varied and the space through which return current may flow may be diminished, to regulate the current to suit particular requirements of use. The valve *U* is shown as a ring or cylinder fitting 90 adjustably and loosely in the annular space between the lower receptacle and the filter *T*, so that it affords a return current passage between its upper edge and the upper receptacle, while its body within the filter tubes deters current from flowing between the lower portions of the latter, and its lower part projecting in the dust chamber serves as an annular wall around the upper part of the tailings cone to prevent eddying currents from approaching the bottoms of 95 the filter tubes.

100 This valve *U* may be adjusted in any suitable way, but I prefer to sustain it by 110 adjustable feet *t* projecting outwardly beneath the filter and carried by cables *u* outwardly of the latter which are wound on adjusting shafts *v* extending through the recess *g* on each side of the receptacle *K* 115 so that by turning these shafts with the hand-wheel *w* the damper *U* may be raised at four points to move it uniformly. A ratchet *x* is provided for locking it. The cables *u* being outside the filter have easy 120 access for striking or grasping or rattling them to move, and thus jar or shake the damper to insure its proper descent. The brackets *t* serve as feet to bear on the outer cone *c* when the damper is in its lowermost 125 position, and they are provided with additional holes *z* so that the damper may be bolted higher or lower on the feet to vary its initial position for adjustments additional to the range of movement of the brackets. The brackets are preferably ex-

130

tended to form guides for the damper so that their outer ends slide against the cylindrical wall *b* to preserve the damper in position between the filter and the tailings cone.

According to another feature of improvement I preferably provide a damper *V* outside of and surrounding the filter troughs and vertically adjustable to vary the inlet thereto. This preferably consists of a ring or cylinder surrounding the lower ends of the filter troughs at the same height as the upper edge of the damper *U* and movable therewith, and as shown is mounted on the 15 feet *t* and adjustable upwardly toward the upper receptacle and this has the function of deterring air currents from flowing inwardly toward the lower part of the troughs to reduce tendency to upward eddies in 20 these, and prevent molestation of the particles descending therein, and the space between the inner and outer dampers serves as a confined annular conduit for conducting dust discharged by the tubes into the 25 calm of the lower dust chamber and isolating the lower end of the tubes from the strong currents above.

According to another feature of improvement I provide a valve *W* surrounding the 30 outer part of the upper receptacle and adjustable downwardly toward the inner side of the lower receptacle which projects outwardly of it, so that this valve may vary the space between its lower edge and the inner receptacle through which return current may pass. This valve is preferably mounted within the filter and between it and the upper receptacle to vary the inlet through the filter to the return passage, and 35 is preferably mounted on the other end of the cable *u* and operated by the shaft *v* on which the cable is fixed so that the upper valve *W* has the tendency to counterbalance the lower valve *U* and they preferably work 40 simultaneously in opposition when used together and not operated independently, and each is independently adjustable as by the turn buckle *w* in the cable. This leg of the cable *u* passes through the shelf afforded 45 by the angle irons or segments *l* suspending the filter tubes, one of which segments is hinged or pivoted so that its section of filter tubes may be swung outwardly to give 50 access to this valve and serves as a door through the filter when the valves are adjusted or removed from the path of this section.

According to another feature of improvement I provide a bifurcated tailings outlet 55 *X* with an adjustable valve *x* as a swinging or flapper valve therein by which the discharge can be divided as desired between the two legs or confined to one or the other leg so that either leg may be used for normal discharge and the other for testing or

measuring purposes, or the discharge may be apportioned between a plurality of receptacles.

According to another feature of improvement I provide a testing or measuring fine 70 outlet *Y* comprising a swinging damper and door *Z* by which the fine discharge may be diverted through the opening *a'* when the damper is thrown to the closed position as shown in dotted lines, in moving to which 75 its handle will automatically open the door *b'* which is fulcrumed on its shaft with a lost motion so that the handle will strike and lift the door as the damper closes and permit the door to close by gravity as the 80 damper opens.

My invention also provides means to position the filter troughs yieldingly and adjustably and for jarring them impactively, and preferably for this purpose screws *c'* 85 engage their lower ends and are drawn outwardly by springs *d'* surrounding them outwardly of the casing and reacting against the latter and their outer heads *e'*, so that by turning the screws the lower end of the 90 filter can be centered to suit and held in resilient condition, and from time to time the operator may hammer on the heads of the screws to jar the filter tubes and through them the valves *V* and *U* and the lower receptacle to free them from adhering particles. The upper receptacle is movably sustained on brackets *f'*, which are removable so that the upper receptacle and filter 95 can be lowered through the conical bottom *p* when the lower cone *r* is removable, and the lower part of the lower receptacle is preferably carried fixedly on and removable with the lower part *r* of the lower cone and the upper part of the lower receptacle 100 is preferably fixed removably on the upper part *p* of the lower cone, so that access to the lower receptacle which is separable may be had by removing its lower part with the lower part *r* of the casing without disturbing the upper parts. 105

The feeder disc is preferably vertically adjustable from without the casing, and while revolving if desired to vary the vertical distance through which material must be lifted, and in operation, this disc being disposed at the desired point, material is fed into the upper receptacle, and the upward current floats the fine material into the outer chamber, where the fine particles 115 precipitate and the air current flows through the filter and the return space between the valves *U* and *W* and the upper receptacle to the lower opening *R*. 120

The filter tubes extract particles floating 125 in the return air and deposit them in the dust chamber, the current is varied by adjusting the dampers *U* and *W* to vary the space through which the return current may pass and the speed of the fans or the pro- 130

jection of their blades is regulated or varied from without the casing, and while operating if desired, independently of or simultaneously wth variation of the height of the feed disc D, or adjustment of the dampers U and W, to vary the force speed or volume of the current to adapt it to such variations or adjustments or to the material being separated, or to the fineness of product desired, 5 or to suit requirements. Tests of efficiency and capacity and fineness, during operation are made from time to time at the respective spouts or coarse and fine outlets and simultaneously or successively the feed disc 10 D and fan E are adjusted from without the casing to produce the desired results or to adapt them or either of them to varying conditions, and adherence of material to the filter is reduced by vibrating the tubes. 15 The casing is suitably supported as by outer feet g' and access through the top is provided with one or more suitable hinged or removable manhole covers h' affording access inwardly and outwardly of the upper 20 receptacle, and through the side by hinged 25 wall or cover i' affording an opening to the outer chamber G, and access within the lower receptacle from below is afforded by a hinged door or cover j' on the lower cone r 30 leading into the space around the tailings cone, from which one can disconnect and raise the upper segment m up against the upper receptacle until sufficient room is afforded between the segments of the tailings 35 cone for one to enter.

I preferably mount the hub k' of the fan above its spokes and slidingly mount the feed disc D concentrically of and supported from the driving shaft N so that it can be 40 adjusted vertically by screw threaded or other means to vary the vertical distance through which the material must be lifted from the disc to the fan, or to vary the space between the disc and the surrounding 45 tapering portion of the feed chamber through which the upward current may flow, or to vary the fineness or quantity of the separated material, so that by screwing the feed disc up or down its position can be 50 varied as desired to suit conditions. This can be accomplished in any suitable way, but I prefer to fix the fan hub k' in position on the driving shaft N, and to movably sustain the feed disc D from the driving 55 shaft N by suspending it therefrom so that it can be rotated thereby and moved vertically relatively thereto. In the construction shown in Fig. 1 I set the fan hub k' fixedly on the driving shaft and mount the 60 tubular hub l' of the feed disc slidingly on or around this shaft below the fan hub, and I sustain the hub l' therefrom by a screw threaded connection, as by vertically adjusting bolts m' adjustably sustained by revolving 65 ing screw threaded nuts f' sustained by and

revoluble with and rotative relatively to the driving shaft, so that the disc can be easily adjusted from above by adjusting the screw threaded connection by which it is sustained.

A flexible elastic or yielding strip n' is 70 preferably mounted on the upper edge of the lower receptacle for making a flexible joint between this cone and the filter, as by sliding on the inner damper U to prevent up-flowing currents around the lower receptacle, and I preferably provide collapsible means as the flexible fabric o' between the lower receptacle and the damper U and between the damper U and the filter to retard up-flowing currents or prevent leakage 75 between these; and I preferably provide floating dampers p' at the bottom of the filters of fabric or other suitable material to swing upwardly and close the space between adjacent filter tubes in case up-flowing current 80 should be induced through these. 85

In its preferred form my invention also provides reverse hollow troughs or conduits q' below the lower ends of the upper troughs and having their concave faces under these 90 to serve as conduits for receiving material therefrom and conducting it downwardly, and having their convex backs r' opposed to the inward current to prevent this from molesting descending particles until they 95 have been conducted out of the zone of such currents.

According to another feature of improvement my invention preferably provides an adjustable upper receptacle K and a stationary top shelf f , so that the latter affords a uniform current outlet S, while the former may be adjusted either with the disc D to vary the vertical distance through which material must be lifted to the outlet, and relatively to the disc D to vary the space between the inclined face e and the disc through which current must pass to regulate the intensity of such current at this point. The inclined bottom h of this adjustable receptacle may be used to vary the return current space when as shown the upper receptacle is not movable with the lower receptacle L, but in the construction shown I prefer to utilize the upper inward valve W for determining the space above the lower receptacle and making the upper receptacle movable independently of this valve, so that the latter may be used for this space and the upper receptacle may be lifted at will and then this space adjusted to suit. The upper and lower walls of the upper receptacle may move together when in fixed connection through its intermediate cylindrical wall P as shown, in which case 105 all may be guided by the vertical guide or arm of the bracket f' and the upper receptacle will slide on this arm, its upper open end being guided within the telescopic or expandible joint t' connecting it with 110 115 120 125 130

- the shelf f . The upper receptacle or any of its movable walls may be adjusted in any manner as by a cable u operated by a screw v and hand-wheel w from without the casing. With this arrangement I prefer to mount the filter segments on the arms of the brackets f' around the upper receptacle so that the filter will be independent of movements of the latter.
- According to another feature of improvement I provide means x hinged to the dampers for swinging, shaking or vibrating them to jar them and the filter and cone for shaking the parts into position or dislodging adhering material, and I mount these parts loosely so that these can swing, jar or vibrate. Preferably the dampers are so suspended that they may vibrate or swing in fluctuations of the current to automatically shake the adjacent parts and thus keep them clear of adhering material, and the lower dampers are so mounted that they have a tendency to move toward the position of maximum opening so that accidental loosening or falling will tend to open instead of close communication through the passages and thus avoid stoppage, and their feet or supports are arranged to afford clearance for passage of material below them even should they fall to the lowermost possible position.
- According to another feature of improvement I preferably provide a revoluble hopper C slidably enclosing the upper end of the feed pipe O which is adjustable therein, the hopper preferably having a through bore y clearing the pipe so that the latter may be removed or inserted through the hopper without other disturbance, which affords a top open part z in line with the pipe through which access for clearing the latter may be had in operation and a removable cover a preferably closes this opening. Preferably the hopper is provided with a keyway or slide b and the head of a bolt c connected to the feed pipe fits this key way and slides therein, and an adjusting screw d above the hopper engages this bolt for adjusting the pipe vertically to regulate the feed delivered to the disc.
- For regulating the flow of feed to the pipe O I prefer to provide an adjustable feed gate e adjusted by a screw f which controls the inclined inlet conduit g to gradually and regularly discharge material therefrom which may be intermittently fed as from the buckets of an elevator not shown or other intermittent sources of supply.
- Another feature of improvement consists of disposing the hopper inlet at one side of and out of line with the feed pipe and providing it with one or more spaced tailings or overflow outlets h and a swinging overflow of tailings chute i so that overflow or tailings may be diverted to either side of the feed pipe and overhead clearance will be afforded above the latter. Preferably a coarse or scalping screen j is mounted above the conduit g and overlaps the chute i so that as material descends through the upper conduit l on this screen the latter will extract coarse pieces and these will be deflected or directed around the feed pipe by the chute i . A cover m closes the conduit l and the reversible chute i , and an open top wall o affords a surface for this chute to set on, where it is preferably held by a pivotal screw n so it can be swung to either side and make a joint with either side of the conduit and with the opposite outlet opening.
- In operation the feed of the hopper being regulated by the gate e and that of the disc being adjusted by the pipe O , and the volume of current being determined by adjusting the speed of the fan, the intensity of the current opposite the disc is determined by adjusting the inclined wall e of the upper receptacle toward or from the disc. The distance through which material must be lifted is determined by adjusting the disc and this being determined the intensity of the current opposite the disc will then be adjusted by adjusting the inclined wall of the upper receptacle toward the disc. Variations in the spaces through which current may flow at other points will then be effected to suit by one or more of the valves until adjustments are arrived at giving the product desired. The action of the current on the movable or vibrating parts will cause a vibration tending to keep the surfaces normally free from adhering particles, and occasionally the parts will be violently agitated from without for complete clearing, or for insuring their movement to proper positions. The hopper will be turned toward the source of supply and the overflow shifted to suit desired discharge, and adjustments and tests may be made during operation.
- It will be seen that this invention provides various improvements in separators which can be readily and advantageously availed of, and it will be understood that the invention is not limited to the particular details, arrangements, combination of features, or uses, set forth as embodying the preferred form of my invention, since my improvements can be availed of in whole or in part according to such modification as circumstances, or the judgment of those skilled in the art, may dictate, without departing from the spirit of the invention.
- One such modification is illustrated in Fig. 3, in which the fan shelf is stationary and the filter T is hung from it, while the upper receptacle has a stationary cylindrical wall K' and oppositely moving tapering walls P' sliding in it to vary the feed chan-

ber F. The lower receptacle L' is here vertically adjustable and slides in a stationary guard wall U' to vary the tailings chamber J. The upper valve W and lower valve V 5 work oppositely and the seals t² are carried on the valve V and close the spaces between the troughs and the guard U'.

The lower reverse troughs q' are preferably hinged to the tips of the upper troughs 10 so that they can swing inwardly and also outwardly until their lower ends rest on the lower conical bottom, and they afford spaces between them through which the current can flow into the dust chamber. A 15 hinged gravity damper r² on the end of the upper tube fitting the concavity of the lower tube opens permitting descent of dust and closes against tendency of current to rise. The bottoms of both rows of troughs are 20 preferably mounted removably on rings or ring segments s² and the spaces between them are preferably closed against up current by a seal t², preferably notched fitting the space between the tubes and mounted on the inner 25 valve U and intermediate valve u². Covers m² and p² are reversibly hinged to the chute i². q² is an annular spacer for the bolts c².

The gate e² protects the disc D from the weight it would carry if the pipe O were 30 full by limiting the feed to that which the pipe is adjusted to discharge.

The brackets f' are preferably pivoted to swing on and be vertically adjusted by screws v² to vary the outlet S by lifting the 35 shelf f, and are clamped by screws w².

The upper body preferably has a fixed skeleton construction consisting of rings x² connected by braces y² on which half of the shell is stationary and the other half is 40 hinged on a vertical rod z², the upper hinged half a³ and the lower hinged half b³ meeting in a flat joint c³ so that either can be swung open separately from the other, and the lower half having a similar flat joint d³ at 45 the bottom so it can be swung free from the outlet pipe I'.

The bolts m' are preferably simultaneously adjusted by a gear e³ engaging their tooth nuts f³.

50 I preferably make the fan blades expandable, as by a supplemental sliding vane g³, operated through a link h³ and a lever i³ from a ring j³ by screws k³ having tooth nuts l³ simultaneously operated by a gear m³ 55 carried by the fan hub and a spring n³ which presses the ring against the screws.

These parts are preferably adjusted from without the casing while running, by any suitable means, as for example by a friction 60 lever o³ operated by an outer handle p³ and engaging the gear e³ to adjust the feed disc, and by a friction lever q³ operated by an outer handle r³ and engaging the gear m³ to adjust the fan blades.

65 For alternately separating materials re-

quiring known differences of lift distances I preferably provide a two phase or multiple position feeder which is quickly shifted from one to another vertical position, as by mounting it with a lost motion. This is 70 preferably done by sustaining the disc D movably on the hub by a ring s³ and cam t³ so that when the cam is raised above the dead center the disc will be at the normal high position and when the cam is 75 dropped the disc will drop to the normal low position, other adjustments being made as to either position as before described.

80 Preferably the disc D is vertically adjustable relatively to the hub for varying its space from the latter, as by mounting it on a ring m⁴ operated by a cam n⁴ to raise or lower the disc on the hub to suit requirements.

85 Preferably the disc is shifted while running as by operating the cams from rods u³ connected to a ring v³ operated by a by-path forked lever w³ from without the casing by a handle x³.

90 Some materials require paddles on the distributing disc, and to provide for quickly utilizing these I preferably mount spaced paddles y³ on a supplementary movable or removable upper feed ring z³, which may be bolted to the feed hub as shown in dotted lines in Fig. 1, when the paddles are not used, or bolted to the disc D, as shown in full lines in Fig. 1, when these paddles are used, and it and the paddles are movable downwardly on to the disc to then afford a supplemental disc with radiating vanes for distributing the material and agitating it while affording current spaces between the blades. The paddle ring is 95 preferably normally removably sustained on the feed hub by bolts a⁴ which can be removed and used to clamp it to the feed disc when this is required.

100 The feed disc is preferably provided with a central outlet b⁴ normally closed by a door c⁴ automatically opened to relieve excessive load, as by trip d⁴ operating its latch e⁴ when the gate descends and thus releasing it. As shown the feed disc is yieldingly mounted on springs f⁴ so that it can descend under abnormal weight, thus bringing the trip d⁴ against the stop g⁴, which itself is 105 preferably carried by a rod h⁴ shown as extending loosely through the feed tube and ending in a handle i⁴ above the hopper, by which handle can be operated to open and close the door c⁴, which latter swings on a hinge j⁴.

110 My invention preferably provides means for automatically regulating the feed, as by utilizing the weight on the feed disc to vary the feed gate e², which is preferably done by operating a wedge k⁴ under the screw f² by a lever l⁴ sustained and operated by the rod h⁴ so that as this rod is pulled down 115

- with the descent of the disc D it withdraws the wedge and lowers the feed gate, thus diminishing feed until the disc is able to distribute it as fast as received, so that the 5 separator can automatically regulate itself and excess will back up in the feed hopper and after filling the latter will overflow through the top outlet which then serves with the by-path σ^4 communicating around 10 the casing and connected with the coarse outlet for returning the scalplings, the overflow if any and the tailings, combined to a pulverizer (not shown) for other treatment, an elevator (not shown) being connected to 15 receive this combined material with fresh supply and refeed it to the hopper, and a storage bin p^4 being provided as a part of an endless circuit to serve as a reservoir for storing temporary excess, in which circuit 20 the separator and the by-path are arranged in multiple so that either may be used to cut out the other without stopping the circuit, or they may be jointly used, one to separate and the other to by-path excess 25 and oversize material. This is shown in Fig. 4, where the valve q^4 shunts or divides discharge from the elevator r^4 between the two separators, and like valves s^4 and t^4 apportion their tailings and fresh feed between the two pulverizers u^4 , and the measuring fine discharge v^4 controls the measuring fresh feed inlet w^4 , from the bin x^4 to proportion fresh feed to finished discharge, by the means illustrated in my application Serial No. 722,233 filed Sept. 25, 1912, for example. The by-path σ^4 is preferably provided with an automatic valve y^4 normally closed to send all material 35 through the separator or automatically 40 opened by the closing of the gate e^2 to then divert all material around the separator. z^4 is a chute communicating between the fine outlet and the bin p^4 for diverting fine product back to the system for re-separation. a^5 is a by-path chute for diverting all or part of the material around the pulverizer, and b^5 is a valve for isolating the pulverizer and returning material to the elevator for re-passage through the separator 45 for further extraction of its fine content in case the separator has left an undue proportion of fines in the returning tailings, which can be cleaned by thus diverting the material around the pulverizer until 50 all fines are extracted from it before refeeding to the latter. y is a collapsible cloth damper around upper part of the filter which descends with the damper W in opposition to the lower dampers, and k^2 is a removable partition enclosing the space 55 above the filters.
- The feed pipe O is normally non-rotary so that material descending through it will not be subject to any centrifugal force tending to hold it against the inner wall of this
- pipe, but this pipe is slidingly keyed within the neck of the hopper C so that it can be turned with the hopper as the latter is adjusted to suit the source of supply of material to be separated, while the pipe 70 can be adjusted vertically, by the screw threaded means c^2 and d^2 which are disposed around it and sustain it from the hopper, toward the disc D to regulate flow of material from the pipe to the disc. The 75 stationary feed pipe O is concentric of the revolving disc D and should be adjusted vertically to approximately follow the vertical adjustments of the disc, and additionally to regulate flow of material from the 80 pipe to the disc.
- The feed disc D is sustained from above, around the non-rotary feed pipe, in any suitable manner so that it can be revolved opposite this pipe to distribute the feed it 85 receives therefrom, and can be adjusted vertically relatively thereto to vary the vertical distance between the disc and the fan shelf f for any of the purposes described. The disc may be thus rotatively and vertically movably mounted around the stationary feed pipe in any suitable or desired way and sustained from any suitable support, but when the disc is mounted to revolve with the fan as shown I prefer to sustain it 90 on the tubular driving shaft N slidingly, around the stationary feed pipe, so that the disc can be screwed vertically relatively to the shaft while it will participate in the revolution of the shaft, so that any variation in the speed of revolution of the shaft N is imparted to both the fan hub and feed disc.
- Although I have shown a stepped pulley 95 on the drive shaft B for varying the speed of revolution of the tubular shaft N and its driven parts, and bevel gears for driving the shaft N from the shaft B, it will be understood that any suitable variable speed or speed changing means may be employed, 100 and any desired driving connection may be utilized for communicating motion to the fan and feed disc, or for varying their speed; and although I prefer to revolve the fan and feed disc similarly and from the 105 one tubular drive shaft N, instead of differentially from independent shafts, it will be understood that my improvements are 110 not limited to this preferred utilization thereof.
- The screw threaded nuts f^3 for vertically adjusting the feed disc, are shown as mounted inside of the casing a and resting on top of the fixed fan hub k' of the tubular vertical shaft N, and as subject to operation 115 from without the casing by a lever o^3 operated by an external handle p^3 frictionally or otherwise separably engaging the rack c^3 to retard it and thus cause the nuts to turn relatively to the screw threaded disc sus- 120

taining members m' on the upper ends of which they screw, but any suitable or desired means around the feed pipe and which will adjustably sustain the feed disc from the drive shaft so that it can be adjusted vertically from above the fan, and preferably from without the casing, may be employed, and such means may be in whole or in part located where convenience declares, although the tubular telescopic sliding mounting of the disc hub l' relative to the tubular shaft N and around the feed pipe O is most convenient in the construction shown.

Likewise the fan varying means, and the means for quickly shifting the position of the feed disc, may be any known or suitable means and either may be disposed where desired, but I prefer the means shown and prefer to dispose each of them within the casing, instead of without it, and to provide means without the casing communicating with them respectively for operating them from without the casing during operation, whereby my improved process of varying the volume of the separating current in its endless path, and of correspondingly or simultaneously varying the point of distribution of the material in the endless current, while feeding material thereto, and while separating the fine material floating therein, may be easily and successfully carried out to vary fineness, change capacity, or suit conditions.

35. What I claim is:

1. In combination, a casing enclosing a chamber, an upper receptacle within said casing having upper and lower openings communicating with said chamber, a lower receptacle within said casing having an open upper end spaced from said upper receptacle and affording communication between said chamber and said lower opening, means for feeding material to be separated into said upper receptacle, means for causing a fluid current to flow through said upper receptacle into said chamber and return between said receptacles to said lower opening, a filter for intercepting particles floating in such current from said chamber toward said lower opening, a valve sustained externally of said upper receptacle and surrounding said lower receptacle for varying the space through which return current may pass from said outer chamber, and means without said upper receptacle and above said filter for operating said valve.
2. In combination, a casing enclosing a chamber, an upper receptacle within said casing having upper and lower openings communicating with said chamber or wall, a lower receptacle within said casing having an open upper end spaced from said upper receptacle and affording communication between said chamber and said lower opening,

means for feeding material to be separated into said upper receptacle, means for causing a fluid current to flow through said upper receptacle into said chamber and return between said receptacles to said lower opening, a filter for intercepting particles floating in such current from said chamber toward said lower opening, and an adjustable valve surrounding said filter for varying the space through which return current may flow thereto.

3. In combination, a casing enclosing a chamber, an upper receptacle within said casing having upper and lower openings communicating with said chamber and having an upper cylindrical outer part, a lower receptacle within said casing having an open upper end spaced from said upper receptacle and affording communication between said chamber and said lower opening, means for feeding material to be separated into said upper receptacle, means for causing a fluid current to flow through said upper receptacle into said chamber and return between said receptacles to said lower opening, a filter for intercepting particles floating in such current from said chamber toward said lower opening, and a valve surrounding and sliding vertically on the cylindrical part of said upper receptacle and adjustable downwardly toward the inner face of said lower receptacle for varying the space between said receptacles through which return current may pass.

4. In combination, a casing enclosing a chamber, an upper receptacle within said casing having upper and lower openings communicating with said chamber, a lower receptacle within said casing having an open upper end spaced from said upper receptacle and affording communication between said chamber and said lower opening, means for feeding material to be separated into said upper receptacle, means for causing a fluid current to flow through said upper receptacle into said chamber and return between said receptacles to said lower opening, a filter for intercepting particles floating in such current from said chamber toward said lower opening, and a valve within and a valve without said filter for varying the space through which current may pass.

5. In combination, a casing enclosing a chamber, an upper receptacle within said casing having upper and lower openings communicating with said chamber, a lower receptacle in said casing having an open upper end spaced from and extending downwardly of said lower receptacle and affording at its outer edge an inlet communicating from said chamber between said receptacles to said lower opening, a valve between said receptacles disposed inwardly of said outer edge and intermediate of said inlet and said

- 5 said receptacles disposed intermediate of said inlet and said lower opening for varying the space between said receptacles through which current returning from said 5 chamber may pass to said lower opening, means for causing a fluid current to circulate upwardly through said upper receptacle into said chamber and return between said receptacles to said lower opening, and a 10 counterbalanced valve concentric of said receptacles for varying the space through which such current may flow.
12. In combination, a casing enclosing a chamber, an upper receptacle in said casing 15 having upper and lower openings communicating with said chamber, a lower receptacle having an open upper end spaced from said upper receptacle and affording communication from said chamber to said lower opening, means for feeding material to be separated into said upper receptacle, means for causing a fluid current to flow up through said upper receptacle into said chamber and return between said receptacles, 20 means for intercepting particles floating in such return current comprising vertically extending hollows affording ways for descending solid particles and intermediate apertures affording current passages between said ways, and means intermediate of said ways for preventing current from flowing upwardly through or between said ways.
13. In combination, a casing enclosing a chamber, an upper receptacle in said casing 25 having upper and lower openings communicating with said chamber, a lower receptacle having an open end spaced from said upper receptacle and affording communication from said chamber to said lower opening, means for feeding material to be separated into said upper receptacle, means for causing a fluid current to flow up through said upper receptacle into said chamber and return between said receptacles, means for intercepting particles floating in such return current comprising vertically extending hollows affording ways for descending solid particles and intermediate apertures affording current passages between said ways, 30 and means in said apertures for preventing current from floating upwardly and inwardly of said filtering means.
14. In combination, a casing enclosing a chamber, an upper receptacle in said casing 35 having upper and lower openings communicating with said chamber, a lower receptacle in said casing affording a return current passage from said chamber to said upper receptacle and an outlet for coarse material, means for causing a fluid current to flow through said upper receptacle to said chamber and return through said passage, and means affording a fine outlet from said chamber having a damper for diverting the 40 fine material, an auxiliary outlet in opera- 45 tive relation to said damper, and a door for said auxiliary outlet operating with said damper.
15. In combination, a casing enclosing a chamber, an upper receptacle in said casing 50 having upper and lower openings communicating with said chamber, a lower receptacle in said casing affording a return current passage from said chamber to said upper receptacle and an outlet for coarse material, 55 means for causing a fluid current to flow through said upper receptacle and through said passage, means for feeding material to be separated into said upper receptacle, foraminous means for intercepting particles floating in such current toward said return passage, and means for vibrating said intercepting means.
16. In combination, a casing enclosing a chamber, an upper receptacle mounted in 60 said casing and having upper and lower openings communicating with said chamber, a lower receptacle mounted in said casing and affording a return current passage communicating between said chamber and said lower opening, means for causing a fluid current to flow upwardly through said upper receptacle into said chamber and return through said passage, means for feeding material to be separated into said upper receptacle, and hinged movable filter means in said casing affording a foraminous filter for intercepting particles floating in such current returning to said passage movable to afford a door between said chamber and said passage.
17. In combination, a casing enclosing a chamber, an upper receptacle in said casing having upper and lower openings communicating with said chamber, a lower receptacle in said casing affording a return passage communicating from said chamber to said upper receptacle and an outlet for coarse material, means for causing a fluid current to flow through said upper receptacle to said chamber and return through said passage, means for feeding material to be separated into said upper receptacle, removable means within said casing affording access within said receptacles and hinged means opposite said removable means affording a swinging door for said casing for affording access to said return passage.
18. In combination, a casing enclosing a chamber and having a tapering lower portion, an inner receptacle in said casing having upper and lower openings communicating with said chamber, means for causing a fluid current to flow through said receptacle and upper opening to said chamber and return through said lower opening, means for feeding material to be separated into said receptacle, removable means within said casing affording access within said receptacles, and hinged means on said tapering 120 125 130 135 140 145 150 155 160 165 170 175 180 185 190 195 200 205 210 215 220 225 230 235 240 - portion and opposite said removable means affording a door for said casing affording access to said receptacle.
19. In combination, a casing enclosing a chamber, a receptacle mounted in said chamber and having upper and lower openings communicating therewith, means affording a passage for return current from said chamber to said lower opening, means for causing a fluid current to flow upwardly through said receptacle and upper opening into said chamber and return through said return passage to said lower opening, means for feeding material to be separated into said receptacle, and adjustable foraminous means for intercepting particles floating in such current disposed in the path of such current returning from said chamber to said lower opening.
20. In combination, a casing enclosing a chamber, a receptacle mounted in said chamber and having upper and lower openings communicating therewith, means affording a passage for return current from said chamber to said lower opening, means for causing a fluid current to flow upwardly through said receptacle and upper opening into said chamber and return through said return passage to said lower opening, means for feeding material to be separated into said receptacle, and resiliently mounted filtering means for intercepting particles floating in such current disposed in the path of flow of such current to said lower opening.
21. In combination, a casing enclosing a chamber, a receptacle mounted in said chamber and having upper and lower openings communicating therewith, means affording a passage for return current from said chamber to said lower opening, means for causing a fluid current to flow upwardly through said receptacle and upper opening into said chamber and return through said return passage to said lower opening, means for feeding material to be separated into said receptacle, interstitial means for intercepting particles floating in such current disposed in the path of flow of such current to said lower opening, and means for impactively jarring such interstitial means.
22. In combination, a casing enclosing a chamber, a receptacle mounted in said chamber and having upper and lower openings communicating therewith, means affording a passage for return current from said chamber to said lower opening, means for causing a fluid current to flow upwardly through said receptacle and upper opening into said chamber and return through said return passage to said lower opening, means for feeding material to be separated into said receptacle, and filtering means for extracting floating particles from such current, and means elastically positioning said filtering means.
23. In combination, a casing enclosing a chamber, an upper receptacle mounted in said casing and having upper and lower openings communicating with said chamber, a lower receptacle affording a return current passage from said chamber to said lower opening, means for causing a fluid current to flow upwardly through said upper receptacle and upper opening to said chamber and return through said passage to said lower opening, means for feeding material to be separated into said upper receptacle, movable means for adjusting the vertical distance through which material must be lifted from said feeding means to said upper opening to regulate the fineness of material carried into said chamber by such current, means for varying the speed of such current, means for varying the space through which such current is permitted to flow to said lower opening, and means for intercepting particles floating in such current in the path of such current flowing from said chamber to said lower opening.
24. In combination, a casing enclosing a chamber, an upper receptacle mounted in said casing and having upper and lower openings communicating with said chamber, a lower receptacle mounted in said chamber and affording communication between the latter and said lower opening, means for feeding material to be separated into said upper receptacle, a revolving fan for causing a fluid current to flow upwardly through said upper receptacle and upper opening into said casing and return through said passage to said lower opening, movable means for adjusting said fan to vary such current, and filtering means for intercepting particles floating in such current disposed in the path of such current flowing between said fan and said lower opening.
25. In combination, a casing enclosing a chamber, an upper receptacle mounted in said casing and having upper and lower openings communicating with said chamber, a fixed receptacle mounted in said chamber and affording communication between the latter and said lower opening, means for feeding material to be separated into said upper receptacle, a revolving fan for causing a fluid current to flow upwardly through said upper receptacle and upper opening into said casing and return through said passage to said lower opening, movable means for adjusting said fan to vary such current, means for varying the space through which such current may flow to such lower opening, and means for intercepting particles floating in such current.
26. In combination, a casing enclosing a chamber, an upper receptacle mounted in said casing and having upper and lower openings communicating with said chamber, a stationary lower receptacle mounted

- in said casing in fixed relation to said upper receptacle affording communication from said chamber to said lower opening between said receptacles and affording a uniform
- 5 vertical distance between said lower opening and the interior of said lower receptacle through which material from said upper receptacle may descend, means for causing a fluid current to flow upwardly in said upper
- 10 receptacle through said upper opening into said casing and return between said receptacles to said lower opening, means for feeding material to be separated into said upper receptacle, and means affording a filter
- 15 for intercepting floating particles in such current flowing from said chamber to said lower opening.
27. In combination, a casing enclosing a chamber, an upper receptacle mounted in said casing and having upper and lower openings communicating with said chamber, a stationary lower receptacle mounted in said casing in fixed relation to said upper receptacle affording communication from
- 25 said chamber to said lower opening between said receptacles and affording a uniform vertical distance between said lower opening and the interior of said lower receptacle through which material from said upper
- 30 receptacle may descend, means for causing a fluid current to flow upwardly in said upper receptacle through said upper opening into said casing and return between said receptacles to said lower opening, means for
- 35 feeding material to be separated into said upper receptacle, a vertically adjustable valve above and without said lower receptacle affording communication from said chamber to said lower opening between its
- 40 edge and said upper receptacle for varying the space between its edge and said upper receptacle through which current may pass, and means affording a filter for intercepting floating particles in such current flowing from said chamber to said lower opening.
28. In combination, a casing enclosing a chamber and having a vertical side portion, a receptacle mounted in said casing and having upper and lower openings communicating with said chamber, means for feeding material to be separated into said receptacle, means for causing a fluid current to flow through said receptacle and upper opening into said chamber and return through said
- 50 lower opening, and vertically sliding means for varying the space through which such current is permitted to flow to said lower opening mounted on said casing and slidingly sustained by said vertical portion.
- 55 29. In combination, a casing enclosing a chamber, an adjustable upper receptacle mounted in said chamber and having upper and lower openings communicating therewith, a lower receptacle mounted in said
- 60 chamber and affording a passage for return
- current communicating between said chamber and said lower opening, a fan revolving in said casing above said upper receptacle for causing a fluid current to flow upwardly through the latter into said chamber and
- 70 return through said passage to said lower opening, comprising a hub, means within said upper receptacle for feeding material to be separated therein comprising a vertically adjustable revolving disc, a revolving shaft
- 75 on which said hub and disc are mounted, and means sustaining said disc from and disposed above said hub.
30. In combination, a casing enclosing a chamber, a receptacle therein having upper and lower openings communicating with said chamber, a revolving fan mounted in said casing for causing a fluid current to flow upwardly through said receptacle through said upper opening to said chamber and return through said lower opening, a revolving feeding disc in said receptacle for feeding material to be separated therein, a vertical shaft carrying said fan and disc for revolving them together, a tubular hopper affording communication through said fan to said disc for feeding material thereto, and a valve in advance of said hopper for regulating flow of material thereto in advance of
- 80 85 90 95
- 95 said disc.
31. In combination, a casing enclosing a chamber, a receptacle in said casing having upper and lower openings communicating with said chamber, a revolving fan in said casing for causing a fluid current to flow up through said receptacle through said upper opening to said casing and return through said lower opening, a revolving disc in said receptacle for feeding material to be separated therein, a tubular shaft for revolving said parts, a tubular feed pipe within said shaft for conducting material therethrough to said disc, a hopper enclosing the upper end of and communicating with said feed pipe for supplying material thereto affording an aperture axially of said feed pipe for access through the latter, and means closing said aperture.
- 100 105 110 115
32. In combination, a casing enclosing a chamber, a receptacle mounted in said casing and having upper and lower openings communicating with said chamber, a revolving fan mounted in said casing for causing a fluid current to flow up through said receptacle into said chamber and return through said lower opening, a revolving disc in said receptacle for feeding material to be separated therein, a tubular shaft for revolving said fan and disc, an adjustable feed pipe traversing said shaft for feeding material to said disc, a hopper above said pipe and means above said hopper and connected to said pipe for adjusting it vertically relatively to said disc.
- 120 125 130
33. In combination, a casing enclosing a

- chamber, a receptacle therein having upper and lower openings communicating with said chamber, means for causing a fluid current to flow through said receptacle and upper opening into said casing and return through said lower opening, means for feeding material to be separated into said receptacle, a feed pipe communicating from said means to above said receptacle, and a hopper communicating with said feed pipe and having overflow outlet conduits at the side of and out of line with said pipe.
34. In combination, a casing enclosing a chamber, a receptacle therein having upper and lower openings communicating with said chamber, means for causing a fluid current to flow through said receptacle and upper opening into said casing and return through said lower opening, means for feeding material to be separated into said receptacle, a feed pipe communicating from said means to above said receptacle, and a hopper communicating with said pipe and having a shiftable overflow chute out of line with said pipe.
35. In combination, a casing enclosing a chamber, means affording a passage for fluid current in said chamber, means for causing a fluid current to flow through said passage, means for feeding pulverulent material to be separated to said passage, and means for intercepting solid particles floating in said current comprising a plurality of vertically extending hollow troughs affording a foraminous wall in said passage having vertically extending hollows in their faces opposed to said current affording downward ways for such particles to descend, and having vertically extending recesses intermediate of said ways affording current passages, and means for covering the longitudinal ends of said recesses and disposed between said troughs for preventing current entering longitudinally of them.
36. In combination, a casing affording a chamber, means affording a current passage communicating with said chamber, means for causing a fluid current to flow through said passage, means for feeding pulverulent material to be separated into such current, and means for intercepting solid particles floating in such current comprising an interstitial member in the path of such current, and a vibratory mounted damper in said casing and in operative relation to said means for varying the space through which such current may flow.
37. In combination, a casing enclosing a current passage, means for causing a fluid current to flow through said passage, means for feeding pulverulent material to such current, means comprising a foraminous wall in said passage for intercepting solid particles floating in such current, and swinging means within said casing and affording a valve in operative relation to said wall for varying the space through which such current may pass.
38. In combination, a casing enclosing a chamber, means affording an annular current passage in said chamber, means for causing a fluid current to flow through said passage, means for feeding material to be separated to said current, means for intercepting solid particles floating in such current comprising an annular series of vertically extending troughs having concave faces opposed to the approaching current, and a vibratory member in operative relation to said troughs and movable to jar said troughs.
39. In combination, a casing enclosing a chamber, an upper receptacle mounted in said casing and having upper and lower openings communicating with said chamber, means for causing a fluid current to flow through said upper opening to said casing and return through said lower opening, means for intercepting floating material in said current comprising an annular series of vertically extending troughs affording current passages between their edges, adjustable means for varying the space through said troughs through which current is permitted to circulate, and yielding means making a flexible sliding joint between said troughs and said adjustable means for avoiding leakage of current between them.
40. In combination, a casing enclosing a chamber, an upper receptacle mounted in said chamber and having upper and lower openings communicating therewith, means for causing a fluid current to flow through said upper opening to said chamber and return through said lower opening, means for feeding material to be separated into said upper receptacle, means for intercepting particles floating in such current toward said lower opening, a lower receptacle below said lower opening projecting within said intercepting means and affording a return current passage therein to said lower opening, and yielding means for avoiding leakage of current between said lower receptacle and said intercepting means.
41. In combination, a casing enclosing a chamber, an upper receptacle mounted in said casing and having upper and lower openings communicating with said chamber, a lower receptacle mounted in said casing and having an open upper end affording a return passage communicating between said chamber and said lower opening, means for causing a fluid current to flow through said upper opening to said chamber and return between said receptacles to said lower opening, means for feeding material to be separated to said upper receptacle, filtering means in the path of such current for inter-

cepting particles floating in such current, and means for varying the space through which such current is permitted to flow comprising a bodily movable loosely sustained vertical annular valve member.

42. In combination, a casing enclosing a chamber, an upper receptacle mounted in said casing and having upper and lower openings communicating with said chamber, a lower receptacle mounted in said casing and having an open upper end affording a return passage communicating between said chamber and said lower opening, means for causing a fluid current to flow through said upper opening to said chamber and return between said receptacles to said lower opening, means for feeding material to be separated to said upper receptacle, and means for varying the space through which such current is permitted to flow comprising a swinging member affording between itself and said upper receptacle a space through which said current may pass between said receptacles.

43. In combination, a casing enclosing a chamber, a receptacle therein having upper and lower openings communicating with said chamber, means for causing a fluid current to flow through said upper opening to said chamber and return to said lower opening, means for feeding material to be separated into said receptacle, means for intercepting particles floating in such current returning to said lower opening comprising vertically extending hollows affording ways for such particles to descend across the path of flow of such current, and means within said casing and beneath said ways for preventing intercepted particles from being molested by such current comprising means affording conduits for such particles below said hollows.

44. In combination, a casing enclosing a chamber, an upper receptacle mounted in said casing and having upper and lower openings communicating with said chamber, a lower receptacle mounted in said casing and having an open upper end affording communication between said chamber and said lower opening, means for causing a fluid current to flow through said upper receptacle through said chamber and return between said receptacles, means for feeding material to be separated into said upper receptacle, means for intercepting particles floating in such current flowing from said chamber to said lower opening comprising vertically extending troughs having their hollow faces opposed to the direction of flow of such current, and means for conducting intercepted particles away from such current comprising downwardly extending troughs having hollows on their faces opposed to the hollows of said first troughs and disposed below and in operative rela-

tion to the latter to receive precipitate therefrom and conduct it downwardly, said troughs affording between their hollows vertically extending passages for such current.

45. In combination, a casing enclosing a chamber, an upper receptacle mounted in said chamber and having upper and lower openings communicating therewith, a lower receptacle mounted in said chamber and having an open upper end affording communication between said receptacles from said chamber to said lower opening, means for causing a fluid current to flow through said upper receptacle and upper opening to said chamber and return between said receptacles through said lower opening, means for feeding material to be separated into said upper receptacle, and means within said casing for jarring said lower receptacle.

46. In combination, a casing enclosing a chamber, an upper receptacle mounted in said chamber and having upper and lower openings communicating therewith, a lower receptacle mounted in said chamber and having an open upper end affording communication between said receptacles from said chamber to said lower opening, means for causing a fluid current to flow through said upper receptacle and upper opening to said chamber and return between said receptacles through said lower opening, means for feeding material to be separated into said upper receptacle, a valve for varying the space through which such current may flow, and means for shaking said valve.

47. In combination, a casing enclosing a chamber, an upper receptacle mounted in said chamber and having upper and lower openings communicating therewith, a lower receptacle mounted in said chamber and having an open upper end affording communication between said receptacles from said chamber to said lower opening, means for causing a fluid current to flow through said upper receptacle and upper opening to said chamber and return between said receptacles through said lower opening, means for feeding material to be separated into said upper receptacle, a valve for varying the space through which current may flow, filtering provisions for intercepting particles floating in such current from said chamber toward said lower opening, and means for shaking said filtering means.

48. In combination, a casing enclosing a chamber, an upper receptacle mounted in said casing and having upper and lower openings communicating with said chamber, a lower receptacle mounted in said casing and having an open upper end affording communication from said chamber to said lower opening, means for causing a fluid current to circulate upwardly through said upper receptacle through said upper opening into said chamber and return between

- 5 said receptacles to said lower opening, means for feeding material to be separated into said upper receptacle, and means for varying the space through which such current is permitted to flow tending to move toward a position to increase such space.
- 10 49. In combination, a casing enclosing a chamber, an upper receptacle mounted in said casing and having upper and lower openings communicating with said chamber, a lower receptacle having an open upper end affording communication between said receptacles from said chamber to said lower opening, means for causing a fluid current 15 to flow up through said upper receptacle through said upper opening to said chamber and return between said receptacles to said lower opening, means for feeding material to be separated to said upper receptacle, a 20 damper for varying the space through which such current is permitted to pass, and collapsible means connected to said damper.
- 25 50. In combination, a casing enclosing a chamber, an upper receptacle mounted in said casing and having upper and lower openings communicating with said chamber, a lower receptacle having an open upper end affording communication between said receptacles from said chamber to said lower opening, means for causing a fluid current 30 to flow up through said upper receptacle through said upper opening to said chamber and return between said receptacles to said lower opening, means for feeding material to be separated to said upper receptacle, a 35 filter for intercepting particles floating in such current returning from said chamber to said lower opening, and flexible means between said filter and said lower receptacle for preventing current leakage between them.
- 40 51. In combination, a casing enclosing a chamber, a receptacle mounted in said casing and having upper and lower openings 45 communicating with said chamber, means for feeding material to be separated into said receptacle, means for causing a fluid current to flow through said receptacle and upper opening into said chamber and return through said lower opening, means for intercepting particles floating in such current affording two successive foraminous walls in the path of such current, and means 55 for varying the space through which such current may flow disposed intermediate of said walls.
- 50 52. In combination, a casing enclosing a chamber, a receptacle therein having upper and lower openings communicating with said chamber, means for feeding material 60 to be separated into said receptacle, means for causing a fluid current to flow through said receptacle and upper opening into said casing and return through said lower opening, means for intercepting particles float- 65
- 70 ing in such current comprising a row of spaced hollow troughs affording current passages between their adjacent edges, and means disposed in the spaces between said troughs for preventing flow of current longitudinally between said troughs extending between their adjacent edges.
- 75 53. In combination, a casing enclosing a chamber, a receptacle mounted in said casing and having upper and lower openings communicating with said chamber, means for causing a fluid current to flow through said receptacle and upper opening to said chamber and return through said lower opening, means for feeding material to be separated into said casing comprising a vertical conduit, a vertically adjustable revolving disc and a plurality of spaced means disposed around said conduit and for adjusting said disc vertically, and means for simultaneously operating said spaced means to equally adjust said disc.
- 80 54. In combination, a casing enclosing a chamber, a receptacle mounted in said casing and having upper and lower openings 85 communicating with said chamber, means for feeding the material to be separated into said receptacle, and means for causing a fluid current to flow through said receptacle and one of said openings into said chamber 90 and return through the other of said openings comprising a revoluble fan having blades variable to vary their superficial area, and means for simultaneously varying said blades.
- 95 55. In combination, a casing enclosing a chamber, a receptacle mounted in said casing and having upper and lower openings 100 communicating with said chamber, means for feeding material to be separated into said receptacle, and means for causing a fluid current to flow through said receptacle and one of said openings into said chamber and return through the other of said openings comprising a fan having outwardly expandible blades to increase their superficial area, and means for simultaneously extending said blades.
- 105 56. In combination, a casing enclosing a chamber, a receptacle mounted in said casing and having upper and lower openings 110 communicating with said chamber, means for feeding material to be separated into said receptacle, and means for causing a fluid current to flow through said receptacle and one of said openings into said chamber and return through the other of said openings comprising a fan having adjustable blades and means for simultaneously adjusting them.
- 115 57. In combination, a casing enclosing a chamber, a receptacle mounted in said casing and having upper and lower openings 120 communicating with said chamber, means for feeding material to be separated into 125

- 5 said receptacle, adjustable revolving means for causing a fluid current to flow through said receptacle and one of said openings into said chamber and return through the other 5 of said openings, and means within said casing for adjusting said revolving means during revolution thereof, and means without said casing for operating said adjusting means.
- 10 58. In combination, a casing enclosing a chamber, a receptacle mounted in said casing and having upper and lower openings communicating with said chamber, means for causing a fluid current to flow through 75 said receptacle and one of said openings into said chamber and return through the other of said openings, a non-rotary feed pipe, suspended vertically adjustable revolving means for feeding material to be separated 80 into said receptacle, and means for adjusting said revolving means during revolution thereof.
- 15 59. In combination, a casing enclosing a chamber, a receptacle mounted in said casing and having upper and lower openings communicating with said chamber, means for causing a fluid current to flow through 85 said receptacle and one of said openings into said chamber and return through the other of said openings, a non-rotary feed pipe, suspended vertically adjustable revolving means for feeding material to be separated 90 into said receptacle, and means for adjusting said revolving means from without said 95 casing.
- 20 60. In combination, a casing enclosing a chamber, a receptacle mounted in said casing and having upper and lower openings communicating with said chamber, means for causing a fluid current to flow through 100 said receptacle and one of said openings into said chamber and return through the other of said openings, a vertical feed conduit, a revolving distributor, for feeding material 105 to be separated into said receptacle operative therein in different vertical positions, and quickly shiftable from one to another of said positions, and means around said conduit for quickly shifting said distributor vertically.
- 25 61. In combination, a casing enclosing a chamber, a receptacle mounted in said casing and having upper and lower openings communicating with said chamber, means 110 for causing a fluid current to flow through said receptacle and one of said openings into said chamber and return through the other of said openings, and revolving means for feeding material to be separated into said 115 receptacle comprising a vertically downwardly yielding feed disc.
- 30 62. In combination, a casing enclosing a chamber, a receptacle mounted in said casing and having upper and lower openings communicating with said chamber, means 120 for causing a fluid current to flow through said receptacle and one of said openings into said chamber and return through the other of said openings, and revolving means for feeding material to be separated into said 125 receptacle comprising a feed disc having an outlet opening downwardly through it, and means for closing said outlet.
- 35 63. In combination, a casing enclosing a chamber, a receptacle mounted in said casing and having upper and lower openings communicating with said chamber, means for causing a fluid current to flow through 130 said receptacle and one of said openings into said chamber and return through the other of said openings, revolving means for feeding material to be separated into said receptacle comprising a feed disc having an outlet door, and means for opening said outlet during revolution of said disc.
- 40 64. In combination, a casing enclosing a chamber, a receptacle mounted in said casing and having upper and lower openings communicating with said chamber, means for causing a fluid current to flow through 135 said receptacle and one of said openings into said chamber and return through the other of said openings, revolving means for feeding material to be separated into said receptacle comprising a feed disc having an outlet door, and means for opening said outlet from without said casing.
- 45 65. In combination, a casing enclosing a chamber, a receptacle mounted in said casing and having upper and lower openings communicating with said chamber, means for causing a fluid current to flow through 140 said receptacle and one of said openings into said chamber and return through the other of said openings, and revolving means for feeding material to be separated into said receptacle comprising a feed disc and means for automatically relieving it of overload.
- 50 66. In combination, a casing enclosing a chamber, a receptacle mounted in said casing and having upper and lower openings communicating with said chamber, means for causing a fluid current to flow through 145 said receptacle and one of said openings into said chamber and return through the other of said openings, and revolving means for feeding material to be separated into said receptacle comprising a feed disc and distributing vanes movable into operative relation therewith.
- 55 67. In combination, a casing enclosing a chamber, a receptacle mounted in said casing and having upper and lower openings communicating with said chamber, means for causing a fluid current to flow through 150 said receptacle and one of said openings into said chamber and return through the other of said openings, means for feeding material to be separated into said receptacle comprising a feed disc having an outlet opening downwardly through it, and means for closing said outlet.
- 60 68. In combination, a casing enclosing a chamber, a receptacle mounted in said casing and having upper and lower openings communicating with said chamber, means for causing a fluid current to flow through 155 said receptacle and one of said openings into said chamber and return through the other of said openings, means for feeding material to be separated into said receptacle comprising a feed disc having an outlet door, and means for opening said outlet during revolution of said disc.
- 65 69. In combination, a casing enclosing a chamber, a receptacle mounted in said casing and having upper and lower openings communicating with said chamber, means for causing a fluid current to flow through 160 said receptacle and one of said openings into said chamber and return through the other of said openings, and revolving means for feeding material to be separated into said receptacle comprising a feed disc having an outlet door, and means for opening said outlet from without said casing.

- means for feeding such material to said feeding means, and means operated by said first feeding means for operating said second feeding means.
5. 68. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for feeding such material to said feeding means, and means automatically operated by said feeding means controlling flow of said material thereto. 70
10. 69. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, and means for automatically varying the quantity of material fed into said receptacle. 75
15. 70. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for adjusting such feed to said feeding means, and adjustable means for varying feed to said adjusting means. 80
20. 71. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for restricting feed to said feeding means, means affording a conduit to said restricting means, means affording an outlet for coarse material from said chamber, and means affording a by-path around said casing communicating between said conduit and said outlet. 85
25. 72. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle comprising a relief outlet therewith, means affording a relief outlet from said casing, means affording a conduit communicating with said feeding means, and means affording a conduit communicating with said conduit and with said outlet around said casing. 90
30. 73. In combination, a casing enclosing a chamber, a receptacle mounted in said casing and having upper and lower openings communicating with said chamber, means for causing a fluid current to flow through said receptacle and upper opening into said chamber and return through said lower opening, means for feeding material to be separated into said receptacle, means affording an inlet to said casing for material to be separated, means affording an outlet from said receptacle for coarse material, means affording an outlet from said casing for separated material, means for supplying material to be separated to said casing comprising an endless path for material and a discharge conduit communicating between said path and said inlet, means affording a return conduit communicating between said outlet for separated material and such endless path, and means for diverting separated material from said casing to such endless path for the return of such separated material to said inlet. 95
35. 74. In combination, a casing enclosing a chamber, a receptacle mounted in said casing and having upper and lower openings communicating with said chamber, means for causing a fluid current to flow through said receptacle and upper opening into said chamber and return through said lower opening, means for feeding material to be separated into said receptacle, means affording an inlet to said casing for such material, means affording an outlet from said casing for separated material, means affording an outlet from said receptacle for coarse material, means for supplying to said casing material to be separated comprising an endless path for such material, and a discharge outlet communicating between said path and said inlet, means affording a conduit communicating between said coarse outlet and such endless path, and means for diverting coarse material from said coarse outlet into said conduit for returning such material to said inlet. 100
40. 75. In combination, a casing enclosing a chamber, a receptacle mounted in said chamber and having upper and lower openings communicating therewith, means for feeding material to be separated to said receptacle, means for causing a fluid current to flow through said receptacle and upper opening into said chamber and return through said lower opening, means affording an outlet from said casing for separated material, means affording an outlet from said receptacle- 105
45. 76. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for restricting feed to said feeding means, means affording a conduit to said restricting means, means affording an outlet for coarse material from said chamber, and means affording a by-path around said casing communicating between said conduit and said outlet. 110
50. 77. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for adjusting such feed to said feeding means, and adjustable means for varying feed to said adjusting means. 115
55. 78. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for restricting feed to said feeding means, means affording a conduit to said restricting means, means affording an outlet for coarse material from said chamber, and means affording a by-path around said casing communicating between said conduit and said outlet. 120
60. 79. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for causing a fluid current to flow through said receptacle and upper opening into said chamber and return through said lower opening, means affording an outlet from said casing for separated material, means affording an outlet from said receptacle- 125
65. 80. In combination, a casing enclosing a chamber, a receptacle mounted in said casing and having upper and lower openings communicating with said chamber, means for causing a fluid current to flow through said receptacle and one of said openings into said chamber and return through the other of said openings, means for feeding material to be separated into said receptacle, means for causing a fluid current to flow through said receptacle and upper opening into said chamber and return through said lower opening, means affording an outlet from said casing for separated material, means affording an outlet from said receptacle- 130

- cle for coarse material, means for supplying material to be separated to said casing, means affording a measured inlet for material to be separated to said casing, means affording an overflow passage for material to be separated communicating with said supplying means in advance of said measured inlet, means affording an endless path for material to be separated comprising a discharge outlet communicating with said supplying means in advance of said measured inlet, and means affording a conduit communicating between said overflow passage and said endless path, for conducting excess of such material overflowing from said measured inlet to said endless path for return to said supplying means.
76. In combination, two casings each enclosing a chamber, receptacles mounted in said chambers respectively and each having upper and lower openings communicating with the chamber in which it is mounted, means in said receptacles respectively for feeding material to be separated thereto, means in said casings respectively for causing fluid currents to flow through said receptacles and upper openings into said chambers and return to said lower openings, means on said casings respectively affording an inlet thereto for material to be separated, means on said casings respectively affording an outlet therefrom for separated material, means below said receptacles respectively affording an outlet therefrom for coarse material, means for supplying material to be separated to both said receptacles comprising an endless path for such material and discharge outlets communicating between such path and said inlets respectively, means affording conduits for coarse material communicating between such path and said coarse outlets respectively, and adjustable means between such path and said discharge outlets controlling discharge of material from such path to such discharge outlets.
77. In combination, a casing enclosing a chamber, a receptacle mounted in said chamber and having upper and lower openings communicating therewith, means for feeding material to be separated into said receptacle, means for causing a fluid current to flow through said receptacle and upper opening into said chamber and return through said lower opening, means affording an outlet from said casing for separated material, means affording an outlet from said receptacle for coarse material, elevating means for elevating material to be separated affording an endless path for such material and a discharge outlet communicating between said path and said inlet, means affording a coarse conduit communicating between said coarse outlet and said elevating means, means affording an inlet for fresh material communicating with said coarse conduit between said coarse outlet and said elevating means, and means in the path of such fresh material for resisting inflow to the latter during the presence of such coarse material in such coarse conduit.
78. In combination, a casing enclosing a chamber, a receptacle mounted in said chamber and having upper and lower openings communicating therewith, means for feeding material to be separated into said receptacle, means for causing a fluid current to flow through said receptacle and upper opening into said chamber and return through said lower opening, means affording an outlet from said casing for separated material, means affording an outlet from said receptacle for coarse material, means affording an endless path through and without said casing communicating with and receiving coarse material from said coarse outlet and communicating with and returning such coarse material to said inlet, means for supplying fresh material to be separated communicating with such endless path, and means in such endless path for retarding supply of such fresh material thereto during the presence of such coarse material therein.
79. In combination, a casing enclosing a chamber, a receptacle mounted in said chamber and having upper and lower openings communicating therewith, means for feeding material to be separated into said receptacle, means for causing a fluid current to flow through said receptacle and upper opening into said chamber and return through said lower opening, means affording an inlet to said casing for material to be separated, means affording an outlet from said casing for separated material, means affording an outlet from said receptacle for coarse material, elevating means affording an endless path for material to be separated and comprising a discharge outlet communicating with said inlet, means affording communication between said coarse outlet and said elevating means, means affording a source of supply for fresh material communicating with said elevating means, means affording communication between said discharge outlet and said source of supply, and movable means for apportioning between said inlet and said source of supply material discharged from said discharge outlet.
80. In combination, a casing enclosing a chamber, a receptacle mounted in said chamber and having upper and lower openings communicating therewith, means for causing a fluid current to flow through said receptacle and upper opening into said chamber and return through said lower opening, means for feeding material to be separated into said casing comprising a non-rotary

- tubular conduit within said casing, vertically adjustable revolving suspended means opposite said feeding means for distributing such material within said receptacle, means without and around said tubular conduit adjustably suspending said distributing means, means without and around said conduit for adjusting said suspending means, and means without said casing for operating said adjusting means. 70
81. In combination, a casing enclosing a chamber, a receptacle mounted in said chamber and having upper and lower openings communicating therewith, means for causing a fluid current to flow through said receptacle and upper opening into said chamber and return through said lower opening, means for feeding material to be separated into said casing comprising a non-rotary tubular conduit within said casing, vertically adjustable revolving suspended means opposite said feeding means for distributing such material within said receptacle, means without and around said tubular conduit adjustably suspending said distributing means, means without and around said conduit for operating said adjusting means during revolution of said distributing means. 75
82. In combination, a casing enclosing a chamber, a receptacle mounted in said chamber and having upper and lower openings communicating therewith, means for causing a fluid current to flow through said receptacle and upper opening into said chamber and return through said lower opening comprising a revolving fan surrounding said conduit, means for revolving said fan, vertically adjustable suspended revolving means for distributing such material into said receptacle, and adjustable means above said fan and without and around said conduit sustaining said distributing means and accessible above said fan to vertically adjust said distributing means. 80
83. In combination, a casing enclosing a chamber, a receptacle mounted in said chamber and having upper and lower openings communicating therewith, means for causing a fluid current to flow through said receptacle and upper opening into said chamber and return through said lower opening, means for feeding material to be separated into said casing comprising a non-rotary tubular conduit within said casing, vertically adjustable revolving suspended means opposite said feeding means for distributing such material within said receptacle, a tubular drive shaft surrounding said feeding means for revolving said distributing means 85
- around said feeding means, adjusting means around said conduit adjustably suspending said distributing means from said shaft and operating means without said casing for operating said adjusting means. 90
84. In combination, a casing enclosing a chamber, a receptacle mounted in said chamber having upper and lower openings communicating therewith, a revolving fan within said casing for causing a fluid current to flow through said receptacle and upper opening into said chamber and return through said lower opening, means for feeding material to be separated into said casing comprising a non-rotary tubular conduit opening therein below said fan, vertically adjustable suspended revolving means for distributing such material into said receptacle and disposed opposite said conduit, means without and around said conduit adjustably suspending said distributing means, and means without said casing for operating said adjusting means to vary said distributing means vertically. 95
85. In combination, a casing enclosing a chamber, a receptacle therein having upper and lower openings communicating with said chamber, means for feeding material to be separated into said casing comprising a tubular conduit therein, means for causing a fluid current to flow through said receptacle and upper opening into said chamber and return through said lower opening comprising a revolving fan surrounding said conduit, means for revolving said fan, vertically adjustable suspended revolving means for distributing such material into said receptacle, and adjustable means above said fan and without and around said conduit sustaining said distributing means and accessible above said fan to vertically adjust said distributing means. 100
86. In combination, a casing enclosing a chamber, a receptacle mounted in said chamber having upper and lower openings communicating therewith, means for feeding material to be separated into said casing, means for causing a fluid current to flow through said receptacle and upper opening into said chamber and return through said lower opening comprising a revolving fan, means for distributing such material in said receptacle comprising a revolving vertically adjustable member, a tubular drive shaft sustaining and driving said fan and member, means without said casing for adjusting said member vertically relatively to said fan, and means without said casing for varying the speed of revolution of said shaft. 105
87. The improved process of separating fine from coarse material consisting in distributing such material in a rising fluid current, vertically varying the point of distribution of such material in such current 110
- 120
- 125
- 130

during such distribution, volumetrically varying such current during such distribution, circulating such current in an endless path, and extracting floating material from such current during such circulation.

88. In combination, a casing enclosing a chamber, a receptacle mounted in said chamber and having upper and lower openings communicating therewith, means for feeding material to be separated into said receptacle, means in said casing and above said upper opening for causing a fluid current to flow through said receptacle and upper opening into said chamber and return through said lower opening, a revolving tubular shaft within said casing and carrying said current means, a pipe within said shaft for conducting such material from without said casing into said receptacle, means in said receptacle and below said pipe for distributing said material in the path of such current, and revolving vanes above said distributing means and a substantial distance below said upper opening carried and revolved by said shaft and projecting radially therefrom into the path of such current for impelling it.
89. In combination, a casing enclosing a chamber, a receptacle mounted in said casing and having spaced upper and lower openings communicating with said chamber, means in said chamber above said upper opening for causing a fluid current to flow through said receptacle and upper opening into said chamber and return through said lower opening, a revolving shaft in said receptacle and revolving said current means,

means in said receptacle below said shaft for distributing material to be separated in the path of such current, and revolving ⁴⁰ vanes carried and revolved by said shaft and projecting substantially radially thereof in to the path of such current and disposed within said receptacle above said distributing means and a substantial distance ⁴⁵ below said upper opening for impelling such current.

90. In combination, a casing enclosing a separating chamber and having a surrounding wall having a lower air inlet opening ⁵⁰ and an upper air outlet opening, means for causing a fluid current to circulate through an endless path through said casing and said upper opening and to return through said lower opening, means within said casing and spaced below said upper opening and above said lower opening for distributing material to be separated in the path of such current, a shaft within said casing revolving about a vertical axis, and vanes ⁶⁰ carried by and revolving with said shaft and projecting substantially radially therefrom into the path of such current, and disposed within said chamber above said distributing means and a substantial distance ⁶⁵ below said upper opening for impelling such current.

In witness whereof, I have hereunto signed my name in the presence of two subscribing witnesses.

GEORGE HOLT FRASER.
